United States Patent Office

Des. 228,684

Patented Oct. 16, 1973

228,684

DRINKING WATER DISPENSER

Lloyd M. Cannon, Grove City, and William Taylor, Columbus, Ohio, assignors to Ebcu Manufacturing Company, Columbus, Ohio

Filed May 17, 1971, Ser. No. 144,367

Term of patent 14 years

Int. Cl. D23—01

U.S. Cl. D67—4

FIG. 1 is a perspective view of a drinking water dispenser showing our new design;

FIG. 2 is a side elevational view;

FIG. 3 is a rear elevational view; and

FIG. 4 is a top plan view thereof.

We claim:

The ornamental design for a drinking water dispenser, substantially as shown.
